GARMENT HANGER

Leon Levin, New York, N. Y.

Application January 18, 1947, Serial No. 722,786

2 Claims. (Cl. 223—91)

1

My invention relates to hangers for garments and, preferably, to that type of hangers which comprises a garment carrying bar consisting of an arched upper part and a rod connecting the ends of this upper part whereby the hanger is adapted to carry several and different garments, for example, all pieces of a suit or to carry garments with arched shoulders as well as garments with straight folding lines.

It is known to use a hanger of this type for the suspension of trousers or similar garments in such a manner that a bent or folded part of the garment is placed over the lower rod of the hanger. A severe disadvantage of this method is that the garment easily slips from the rod and slides down along the front or the back of the rod. Objects of my invention are to avoid this drawback, to secure the suspended garment to the rod, and to avoid the necessity to suspend the garment in a carefully balanced position.

Other objects are to provide for easy and quick attachment of a garment to the rod of the hanger and for easy and quick disengagement of the garment, to provide one or two clamping members which are slideable along the rod and which can be brought into a garment clamping position and can be withdrawn from the clamping position by sliding movement, and to secure the clamping member in any of its sliding positions by frictional engagement with the rod.

Further objects are to provide for suitable strength and rigidity of the rod guiding the clamping members, to provide the rod with a relatively broad surface which is positioned about parallel to gripping surfaces of the clamping members whereby a garment can be inserted between these surfaces, and to provide the clamping members with resilient tongues having these gripping surfaces whereby the inserted garment is held by resilient pressure.

Still further objects are to attain these results with simple, inexpensive and reliable means, and to provide for an easy assemblage of the rod and the clamping members.

Still other objects and advantages will appear from the following description of an exemplifying embodiment of my invention, from the appended claims and from the accompanying drawings in which:

Fig. 1 shows a side view of an illustrative embodiment of my invention on a reduced scale.

Fig. 2 shows a part of Fig. 1 on a larger scale, this part comprising a broken off part of the lower rod represented non-sectionally and a clamping

2

member represented cut along the line 2—2 in Fig. 3.

Fig. 3 shows a cross-section taken along the line 3—3 in Fig. 2.

Fig. 4 shows a cross-section taken along the line 4—4 in Fig. 2.

Referring to the drawing, numeral 1 indicates the central part of a hanger body. The part 1 is adapted for suspension, for example, by providing the same with a hook 5 extending from the central part 1 upwardly. The body of the hanger further comprises two wings 6 sloping from the central part 1 in opposite directions, and a rod 7 connecting the outer or lower ends 10 of the wings 6. The parts 1, 5, 6 and 7 may form one piece made of plastics or of any other suitable material.

The rod 7 has a narrower part 8 and a broader part 9 positioned on top of the part 8. Another 20 broader part 10 is preferably positioned below the part 8 whereby the cross-section of the rod is shaped like an I. The upper surface of the part 8 or of the rod 7 is smooth and adapted to support a garment placed on and depending from the rod. The front and back portions of the parts 9 and 10 form rims projecting beyond the part 8. These projecting rims may have continuations 11 and 12 running along the entire outlines of the hanger body.

30 A member 13 is slideable along the rod 7 or along a suitable part of the rod's length. Preferably, another identically shaped member 14 is positioned symmetrically to the member 13. The following description of the member 13 applies to the member 14 correspondingly.

The member 13 is made of suitably strong and 40 resilient material, for example, of plastics. The member has a longitudinal channel slidably fitting the part 9 of the rod 7. This channel has a ceiling or upper surface 15 contacting the upper surface of the rod 7 and has a bottom with a slot 16 for the passage of the part 8 of the rod. The surface 15 may be interrupted by slots 17 separating resiliently bendable lateral walls or wings 45 18 from the central part of the member 13. Each wing 18 forms a lateral wall of the channel of the member 13, has a surface 19 contacting a side of the part 9 and has an inwardly directed projection 20 reaching under a rim of the part 9 and 50 contacting the lower surface of this rim.

55 Preferably, the wings 18 have such a distance from each other that the surfaces 19 slightly press against the part 9 whereby some friction exists between the rod 7 and the member 13 and the latter will not slide, except when this friction is

overcome by intentional application of force. The friction and the engagement between the rod and the member 13 is preferably increased by a suitably uneven shape of the contacting surfaces. For example, the surfaces 19 are serrated or wavy and the contacting surfaces of the part 9 have corresponding serrations or waves 21 whereby each of these surfaces shows projections and recesses alternating in the longitudinal direction of the rod 7.

The member 13 is brought into slidable engagement with the rod 7 by spreading the resilient wings 18 and moving the member 13 down until the surface 15 contacts the upper surface of the rod and the projections 20 snap under the rim of the part 9. Preferably, the lower inner edges of the projections 20 are cut obliquely by surfaces 28 converging in upward direction whereby the wings 18 will spread automatically when the member 13 is pressed down over the part 9.

The serrations or waves 21 may extend over the entire length of the rod 7 or, preferably, over portions of this length extending from the line 22 to the line 23 and from the line 24 to the line 25 in Fig. 1 whereby the member 13 can move between the lines 22 and 23 and the member 14 can move between the lines 24 and 25.

The member 13 has a tongue or projection 26 extending at a small distance over a rod 7 in a direction toward the center of the rod or toward the member 14. Preferably, the direction of the tongue 26 is slightly sloping toward the free end of the tongue whereby upwardly directed pressure will bring the tongue into a position about parallel to the upper surface of the rod. The tongue is resilient and forms a flat spring having a lower gripping surface 27.

Before a garment is attached to the rod 7, the members 13 and 14 are moved to positions remote from the center of the rod. After a suitable part or parts of a garment, for example, the foot ends of a pair of trousers have been placed on the rod 7, these members are moved toward the center of the rod as far as necessary to clamp the garment between the rod and the tongues 26. In this position, the tongues press the garment resiliently against the rod, whereby the garment is secured to the rod. When the garment is to be taken off the hanger, the members 13 and 14 are withdrawn from the clamping positions to the outer sides.

I desire it understood that my invention is not confined to the particular embodiment shown

and described, the same being merely illustrative, and that my invention may be carried out in other ways without departing from the spirit of my invention as it is obvious that the particular embodiment shown and described is only one of the many that may be employed to attain the objects of my invention.

Having described the nature of my invention, what I claim and desire to protect by Letters 10 Patent is:

1. A garment hanger comprising a part adapted to be suspended, a horizontal rod having ends connected to said part, and two members slidably on said rod, each having a resilient projection 15 forming an elongated tongue extending over said rod toward the corresponding projection of the other member at such a distance from said rod that a channel of small height and considerable width is left between said rod and each of said tongues, and that said two channels have facing open sides whereby a garment part can be clamped between said tongues and said rod in a position where said garment part overlies said rod and extends in straight direction from one 20 of said channels to the other.

2. A garment hanger comprising a rod, means for suspending said rod in a horizontal position, a member slidably on said rod, having a surface contacting said rod from the upper side, having lateral walls contacting lateral surfaces of said rod and having inwardly directed projections contacting said rod from the lower side, and a clamping tongue affixed to said member and extending over said rod at a small distance therefrom, the 30 contacted lateral surfaces of said rod having longitudinally alternating waved-shaped projections and recesses, and the surfaces of said walls contacting said lateral rod surfaces having projections and recesses corresponding to said first 35 projections and recesses.
